UNITED STATES PATENT OFFICE.

GEORGE C. L. TISCH, OF ELIZABETH, NEW JERSEY.

CHENILLE UNTWISTING AND WINDING MACHINE.

1,398,754.

Specification of Letters Patent.

Patented Nov. 29, 1921.

Application filed June 11, 1920. Serial No. 388,103.

To all whom it may concern:

Be it known that I, GEORGE CHRISTIAN LOUIS TISCH, a citizen of the United States, and a resident of Elizabeth, in the county of Union and State of New Jersey, have invented a new and Improved Chenille Untwisting and Winding Machine, of which the following is a full, clear, and exact description.

10 This invention relates to machines for untwisting chenille as it leaves the chenille forming machines, an object of the invention being to provide an improved construction which will automatically untwist the chenille continuously.

Another object of the invention is to provide a machine timed to operate in proper step with the machine which forms the chenille so that it may produce an untwisting action as fast as the chenille is manufactured, the arrangement being such that the mechanism for untwisting the chenille is comparatively small and, consequently, requires but little space to properly untwist great lengths of chenille.

A still further object of the invention is to provide a machine for untwisting chenille and at the same time winding the untwisted chenille on a drum ready for disposal in any desired manner.

In the accompanying drawings—

Figure 1 is a side view of an untwisting and winding machine disclosing an embodiment of the invention.

35 Fig. 2 is a top plan view with certain parts broken away of the machine shown in Fig. 1.

Referring to the accompanying drawings by numerals, 1 indicates a base of any desired character provided with a frame 2 having suitable bearings to receive certain shafts hereinafter fully described.

Heretofore, in the manufacture of chenille as it comes from the machine, it is moved over a table or platform where the full length of the chenille, as for instance, twenty or thirty yards, usually six strands are manufactured at one time and moved simultaneously over a table. However, this requires a large amount of space in the factory and in addition, after the chenille has been laid out lengthwise on the table, it has to be untwisted. Each strand of chenille is taken manually and connected up with the well-known apparatus which is manually rotated and thus the various strips are manu-

ally untwisted. This operation not only requires a large amount of factory space, but is expensive by reason of the use of an extra number of assistants for the untwisting operation.

In the present invention the various strips or cords of chenille are fed directly into the untwisting machine shown in the drawing and are untwisted at the same rate that they are manufactured, and as they are untwisted, they are wound on a drum 3. The drum 3 may be of any desired size and is slidably mounted upon a shaft 6. The shaft is carried by a bracket 7 bolted or otherwise rigidly secured to a sleeve 40 on which is rigidly mounted a pulley 19.

A section 8 of bracket 7 is hinged at 9, and a suitable catch 10 is provided at the upper end of section 8 so that the shaft 6 may be disengaged from bracket 7 at one end in order to allow the spool or drum 3 to be slid off of said shaft and a new one substituted at any time. The spool 3 is connected with a driving disk 11 by any desired means, as for instance, connecting screw 12 which rigidly clamps the disk 11 to the spool, but which may be unscrewed readily at any time.

A spring 13 is provided and positioned to act continually against the disk 11 forcing the same in a certain direction whereby the friction surface 14 of the disk will be pressed against the cone 15. During the winding of the chenille on the spool 3, the cone 15 will be moved gradually away from shaft 6 and consequently, the spool 3 will be moved longitudinally of shaft 6 under the action of spring 13. This gradual movement of the cone 15 away from shaft 6 will continue until it reaches the position shown in Fig. 1 and then will automatically move back unless prevented by stopping the machine or from some other cause. As the surface 14 engages the cone 15 near its greatest periphery, the speed of spool 3 will be greatest and said speed will decrease relative to the movement of cone 15 as said cone moves to the position shown in Fig. 1. The parts are set so that this movement of cone 15 will be in proportion to the matter wound on spool 3. The speed of the spool 3 is slowest when the parts are arranged as shown in Fig. 1 but when the surface 14 of wheel 11 engages the cone 15 near the periphery, the speed of the spool 3 will be greatest in respect to cone 15. This will cause the chenille to be fed in substantially

equal quantities over the entire spool and at approximately the proper speed according to the speed of the other parts.

The cone 15 is rigidly secured in any desired manner with a hollow shaft 16 carried by frame 2, said hollow shaft receiving the chenille 17 from the point where it is manufactured and guiding the same as it moves toward the spool 3. In order that the spool 10 3 and the disk 11 shall rotate, shaft 16 is held stationary by means of the oppositely positioned pins 21 extending into the slots 22 of the bifurcated end 23 of lever 24. The lever 24 is swung back and forth as 15 hereinafter fully described and, consequently, reciprocates shaft 16 and cone 15 without rotating the same. In order that the chenille shall be untwisted, power is transmitted through pulley 19, through the 20 cable or belt 18 from the chenille manufacturing machine or other suitable power, whereby the sleeve 40 is rotated, and, consequently, the bracket 7, disk 11, spool 3, and associated parts. This will cause the 25 disk 11 to roll around the cone 15 and produce a rotary movement of the disk 11 and drum 3 for winding the chenille on the drum 3 as it is untwisted.

The lever 24 is pivotally mounted on shaft 30 25 and has a laterally extending shaft or stud 27 projecting from the lower end thereof on which a link 28 is pivotally mounted. The link at its opposite end is pivotally connected at 29 to a disk 30 which is connected with a worm 31 by a suitable shaft 32. In this way as the worm wheel 31 rotates, the lever 24 will be gradually swung in and out, moving the cone 15 toward and from shaft 6. The worm wheel 31 meshes 40 continually with the worm 33 secured to the shaft 34.

The shaft is journaled in a suitable bearing box in frame 2 and carries a beveled gear 35 at one end. The gear 35 meshes 45 with pinion 36 which is rigidly secured to shaft 37 carrying a sprocket wheel 38. This sprocket wheel receives power from a chain 39. The sprocket chain 39 preferably receives power from the same source as belt 18 50 and is timed to move with said belt so that the back and forth movement of cone 15 will be in proportion to its rotation, whereby the chenille will be untwisted not only as fast as it is manufactured, but it will also be 55 wound upon the spool 3 at the same rate.

Various slight changes might be made in the general form and arrangement of parts described without departing from the invention, and hence I do not limit myself to 60 the precise details set forth, but consider myself at liberty to make such changes and alterations as fairly fall within the spirit and scope of the appended claims.

What I claim is:

65 1. A chenille untwisting machine, com-

prising a drum for receiving chenille, a bracket carrying said drum, a tube directing the chenille to the drum, a cone carried by said tube, said tube being non-rotatable, means connected with the bracket for rotating the same, said drum being rotatably mounted in the bracket so as to rotate independently in a plane at right angles to the plane of rotation of the bracket, a beveled disk connected with said drum and engaging said cone whereby as the bracket and disk are rotated, said disk will frictionally engage the cone and be rotated in a plane at right angles to the rotation of the bracket and thereby rotate said drum, and means 70 causing said disk to press against said cone.

2. An untwisting machine for chenille comprising a drum, a bracket carrying said drum, means for conveying chenille to the drum, mechanism for rotating said bracket 75 in one plane, driving mechanism for said drum, means for rotating said drum in a plane at right angles to the first-mentioned plane, and automatically actuated mechanism for decreasing the speed of rotation 80 of the drum relatively to that of the driving mechanism as the quantity of chenille wound upon the drum is increased.

3. An untwisting machine for chenille comprising a drum, means for guiding 95 chenille to the drum, a bracket carried by said drum, power mechanism for rotating said bracket in one plane, said drum being mounted on said bracket to rotate on its own axis in a plane at right angles to the first-mentioned plane, a friction disk carried by the bracket and engaging said drum for the purpose of rotating the drum on its own axis, a non-rotatable cone engaging said disk in such manner that as the disk is rotated with the bracket, the disk is also turned on its own axis, said drum turning on its own axis for the purpose of winding the chenille upon the drum, and mechanism for moving said cone toward and from 100 said drum during the rotation of said drum in order to vary the speed of rotation of said drum.

4. A device of the character described comprising a drum upon which chenille is to 115 be wound, a driving mechanism connected with said drum for the double purpose of turning said drum on its own axis and of spinning the drum in a plane at right angles to its own axis in order to untwist the 120 chenille as the latter is wound upon the drum, and automatically actuated mechanism interposed between the driving mechanism and the drum for changing the speed of rotation of the drum relatively to the 125 driving mechanism as the chenille is wound upon the drum so as to distribute the chenille evenly upon the drum.

5. A chenille untwisting machine comprising a drum, a tube for guiding chenille 130

to the drum, means for conferring upon said drum a reciprocating motion relatively to said tube, a friction cone rigidly secured to said tube, means for preventing said tube 5 and said friction drum from rotating, a bracket for supporting said drum, driving means for rotating said bracket, a disk connected with said drum and bearing against said friction cone for the purpose of turning 10 the disk and the drum upon their own axes when said bracket is rotated, and spring mechanism connected with said disk for causing said disk to engage said friction cone independently of the position of 15 said friction cone.

6. A chenille unwinding machine comprising a drum for receiving chenille, a bracket carrying said drum, a tubular member for directing the chenille to the drum, a fric-

tion cone carried by said tubular member, 20 said friction cone and said tubular member being non-rotatable, means for rotating said bracket, said drum being revolvably mounted in said bracket so as to rotate in a plane at right angles to the plane of rotation of 25 the bracket, a bevel disk connected with said drum and engaging said cone so as to cause said disk by its frictional engagement with said cone to rotate in a plane at right angles to the rotation of the bracket and 30 thus rotate said drum, means for causing said disk to press against said cone, and mechanism controllable by the rotation of said drum for shifting the position of said drum bodily in relation to said cone so as to 35 change the speed of rotation of said drum upon its own axis.

GEORGE C. L. TISCH.
